UNITED STATES PATENT OFFICE

HOWARD A. WOLF, OF PHILADELPHIA, PENNSYLVANIA, ASSIGNOR TO WOLF BROTHERS, OF PHILADELPHIA, PENNSYLVANIA, A COPARTNERSHIP CONSISTING OF BENJAMIN WOLF, LOUIS WOLF, ALBERT WOLF, HOWARD A. WOLF, AND ELIAS WOLF

DISPENSER

Application filed December 5, 1929. Serial No. 411,723.

This invention relates to a dispenser particularly adapted for the dispensing of flat paper drinking cups or the like.

Heretofore it has been customary to use 5 metallic containers for the dispensing of flat paper drinking cups, the containers having sloping bottoms and being provided with openings through which the drinking cups may be withdrawn one at a time by a user. 10 Containers of this type are of relatively expensive construction and furthermore their charging with loose paper cups is a matter of difficulty.

It is the object of the present invention to 15 provide a pasteboard container for the cups which may be used as a dispenser and which may also be used to facilitate charging of the more elaborate metal dispensers.

Detailed objects of the invention and ad- 20 vantages thereof will be apparent from the following description read in conjunction with the accompanying drawings, in which:

Fig. 1 is a perspective view of the paste- 25 board container illustrating one method of attaching the same to a wall so that it may be used as a dispenser;

Fig. 2 is a top plan view of the container;

Fig. 3 is a bottom plan view of the container;

Fig. 4 is a developed view showing the blank which may be folded to form the container;

Fig. 5 is an illustration of the use of the container in charging a metallic dispenser; 35 and

Fig. 6 is a perspective view illustrating another mode of attachment of the pasteboard container to a wall when used as a dispenser.

Referring first to Fig. 4, which illustrates 40 the blank from which its construction will be clear, it will be seen that the blank consists of a front wall 2, side walls 4 and 6 and a rear wall 8 to which a flat tab 10 carried by the rear end of the side wall 4 may be secured by adhesive. Attached to the upper ends of front wall 2 and rear wall 8, respectively, are the underlying tabs 12 and 14. Arranged to be secured above these walls are the tabs 45 16 and 18 carried by the side walls, ears on the tab 16 being arranged to engage within

slots 20 in the tab 18. Thus there is a closure formed for the top of the dispenser.

A tab 22 is secured to the bottom of the rear wall 8. This tab, in the finished package, is covered by tab 24 carried by the bottom of the side wall 6, which in turn is overlapped by the tab 26 carried by the bottom of the side wall 4, a slot 28 in tab 24 being engaged by an ear 30 on tab 26.

A tab 32 formed as a continuation of the front wall 2 and being demarcated therefrom by a line of perforations 34 is provided with scored lines 36 whereby it may be folded under the dispenser, an ear 38 formed thereon being receivable within a slot 40 carried by the tab 26.

It will be noted that the various walls and tabs are differentiated from each other by scored lines which permit ready folding. The vertical scored lines 42 and 44 are pro- 70 vided so that the dispenser may be flattened out for easy shipment or handling after the tab 10 is adhesively secured to the wall 8. In the finished package, these scored lines have no function.

From the blank it will be clear that the finished container will have the form illus- 75 trated in Fig. 1, that is, in any vertical position the top will be horizontal while the bottom will slope downwardly toward the lower end of the front wall 2.

From Figs. 2 and 3 it will be seen that the horizontal cross section is trapezoidal. The dispenser is adapted to receive cups 54 of the usual trapezoidal form corresponding to the cross section of the dispenser. When the dispenser is adapted to function as such, the tab 32 is torn from the bottom of front wall 2 along the perforated line 34. The cut-away portions 45 of the tabs 24 and 26 permit a user to insert his finger within the bottom of the container to withdraw a cup through the opening formed by the removal of the tab 32. Inasmuch as the opening is just large enough to permit the passage of the shorter closed end of the cup outwardly there- 95 through, the cups will be prevented from slipping out, when removal is not desired, by the enlarged open ends thereof. In other words, to withdraw a cup it is necessary to 100

exert sufficient force to cause a distortion of the upper open end sufficient to permit that end to pass outwardly from the dispenser.

In order to permit the described container 5 to be used satisfactorily as a dispenser, it must be mounted upon a vertical wall or the like. A preferred form of mounting is illustrated in Fig. 1.

10 Openings 46 are provided in the various parts of the bottom tabs adjacent the rear wall to permit the insertion of the upright prongs 48 of the bent-wire hook 50 which is provided with eyes, as illustrated, through which screws may pass to secure it to a wall. 15 The upright members 48 securely hold the dispenser in an upright position tightly against the wall, ready replacements being effected by vertical removal of the exhausted dispenser from the hook and its replacement by 20 a new one.

Instead of the specific holder shown in Fig. 1, other forms of holder may be used. For example, a horizontal slit 52 may be formed in the rear wall 8 of the dispenser arranged 25 to receive a hook of any suitable shape made, for example, of sheet metal and secured to the wall.

Besides being used as a dispenser, the container may be used for charging the ordinary 30 type of metal dispenser illustrated at 56 in Fig. 5. This container is provided with an open bottom through which a finger of the user may be inserted and a horizontal slit 58 in the front through which a cup may be 35 withdrawn. In using the container in a device of this character, the closed container may be dropped within the metal dispenser. The tabs 22, 24, 26 and 32 may then be torn from the container so as to open its entire 40 lower end. The container can then be vertically withdrawn from the dispenser, leaving the cups in proper position. A second container loaded with cups may be dropped upon the charge of cups in the container to act as 45 a weight forcing them down and also to provide the re-fill as soon as the first charge is exhausted.

What I claim and desire to protect by Letters Patent is:

50 1. A container for paper cups consisting of a box formed from a blank of sheet material, said box having a downwardly and forwardly sloping bottom and upright front, back and side walls, a plurality of interengaging 55 flaps joined to the side walls and partially closing the bottom of the box, and a third flap carried by the front wall and defined therefrom by a line of perforations, and extending rearwardly and engaging one of the aforementioned flaps.

60 2. A container for paper cups consisting of a box formed from a blank of sheet material, said box having a downwardly and forwardly sloping bottom and upright front, back and side walls, a plurality of interengaging flaps

joined to the side walls and partially closing the bottom of the box, and a third flap carried by the front wall, defined therefrom by a line of perforations, and releasably held rearwardly over the other flaps.

70 3. A container for paper cups consisting of a box formed from a blank of sheet material, said box having a downwardly and forwardly sloping bottom and upright front, back and side walls, a plurality of interengaging 75 flaps joined to the side walls and partially closing the bottom of the box, said flaps being cut away adjacent the front wall, and a third flap carried by the front wall and defined therefrom by a line of perforations, and extending rearwardly and engaging one of the aforementioned flaps.

80 4. A container for paper cups consisting of a box formed from a blank of sheet material, said box having a downwardly and forwardly 85 sloping bottom and upright front, back and side walls, a plurality of interengaging flaps joined to the side walls and partially closing the bottom of the box, said flaps being cut away adjacent the front wall, and a third 90 flap carried by the front wall, defined therefrom by a line of perforations, and releasably held rearwardly over the other flaps.

95 In testimony of which invention, I have hereunto set my hand, at Philadelphia, Pennsylvania, on this 2nd day of December, 1929.

HOWARD A. WOLF.
